UNITED STATES PATENT OFFICE.

FRANCIS C. SOCIN, OF BROOKLYN, NEW YORK, ASSIGNOR OF ONE-HALF TO WILLIAM B. SCHOFIELD, OF WORCESTER, MASSACHUSETTS.

CATCH.

1,119,892.

Specification of Letters Patent.

Patented Dec. 8, 1914.

Application filed September 12, 1913. Serial No. 789,571.

To all whom it may concern:

Be it known that I, FRANCIS C. SOCIN, a citizen of the United States, residing at Brooklyn, in the county of Kings and State 5 of New York, have invented a new and useful Catch, of which the following is a specification.

This invention relates to a catch for doors, ladders, seats, etc., and for the pivoted covers of boxes, trunks, phonographs, pianos, 10 cases and for various other articles.

The principal objects of the invention are to provide a catch adapted to be connected with the box or the like and cover in such 15 a way that the cover can be held in open position but can be closed readily simply by manipulating the cover without touching the catch, and especially to reduce a catch for this purpose to its simplest terms and 20 minimum cost of manufacture.

Reference is to be had to the accompanying drawings in which,

Figure 1 is a side elevation of a catch constructed in accordance with this invention 25 showing it in position when the cover is open, the box appearing in section; and Fig. 2 is a similar view showing the cover closed.

Although capable of a wide range of utility, the invention is shown as applied to a 30 simple box or the like A having a pivoted cover B. It is to be understood that this may represent a trunk or a receptacle of any kind having such a cover.

The catch is shown in the form of a flat 35 piece of sheet metal 10 pivoted at 11 to the cover and adapted to engage a pin or stud 12 on the box. The catch 10 is in the form of an arm having a longitudinal slot 13 therethrough, said slot being provided with 40 an offset 14 at the front near the bottom. Said offset extends out from the main body of the slot substantially at right angles at the top and at an inclination at the bottom. At the top it has a substantially horizontal 45 surface 15. Below the bottom of the offset there is an inward projection 16 and below that an enlarged opening 17 at the bottom of the slot. The projection 16 extends inwardly into the slot a material distance beyond the outer edge of the slot and therefore beyond the top of the horizontal surface 15. The box is provided with a headed pin 12 in position to enter the slot when the cover is closed and engage the surface 15.

when the cover is open and hold the catch 55 in inclined position.

The operation of the device is very simple. If it is desired to hold the cover in open position, the cover is raised comparatively slowly until the offset 14 receives the 60 pin 12. Then the surface 15 rests on the pin and holds the cover open. As this surface is then at a slight rearward inclination the weight of the catch assists in holding it in that position. When it is desired to close 65 the cover, direct pressure down upon it will simply press the top of this offset against the pin and cannot result in dislodging the latch.

When it is desired to lower the cover, 70 from this position, it is necessary first to raise it slightly until the latch comes up into such position that the pin 12 is in the enlarged opening 17 at the bottom. Then the cover is either dropped or lowered suddenly. The effect of this is to throw the projection 16 against the pin 12 with such force as to throw the whole latch over to the front and it has been found in practice that this throws it far enough so that the 80 latch engages the pin at a point above the substantially horizontal upper wall 15 of the offset 14 and thus the catch is disengaged and the cover can be lowered.

When it is desired to disengage the catch 85 from the headed pin or stud 12 the cover is raised until the pin is in the enlarged opening 17. Then the latch can be moved sideways to disengage it. Normally however the head of the stud overlaps the edge of 90 the slot and holds the latch in position.

It will be understood that the invention can be applied to all kinds of boxes, trunks, cases and the like which have hinged covers, and to ladders, seats, doors, etc.

Although I have illustrated and described only a single form of the invention, I am aware of the fact that modifications can be made therein by any person skilled in the art without departing from the scope of the 100 invention as expressed in the claims. Therefore, I do not wish to be limited to all the details of construction herein shown and described, but

What I do claim is:—

1. The combination with an article having a pivoted member, of a catch pivoted to said member and depending therefrom, said

catch having a slot therealong and said slot having a lateral offset, a surface beyond the offset extending inwardly beyond the rear edge of the offset and an opening beyond 5 said surface, and a projection on the article adapted to enter said slot and engage in the offset.

2. The combination with a box or case and a cover pivoted thereto at the rear, of a 10 catch pivoted to the cover and freely depending therefrom, said catch having a longitudinal slot provided with an offset near the lower end having a horizontal upper 15 wall and also having an enlarged opening at the bottom below said offset and an inward projection just below the offset, and a headed pin mounted on the box or case in position to enter said enlarged opening and having a shank permitting it to pass into the 20 slot and offset, whereby when the cover is raised to a position in which the pin passes into the enlarged opening and then suddenly lowered the catch will be thrown forward by said projection to prevent the pin 25 from passing into said offset.

3. As an article of manufacture, a catch for a pivoted member comprising a flat piece of sheet metal pivoted to the member at its upper end and having a longitudinal slot, 30 said slot being provided with a trans- offset on the front side near the bottom having a horizontal top surface and with an

inwardly extending projection just below the offset longer than the offset, and a pin in position to enter said slot and offset and 35 coöperate therewith.

4. As an article of manufacture, a catch for a pivoted cover comprising a flat piece of sheet metal having a longitudinal slot, 40 said slot being provided with a transverse offset on the front side near the bottom having a horizontal surface and with an inwardly extending projection just below the offset longer than the offset, and an enlarged opening below the projection. 45

5. In a catch, the combination with a projection, of a catch member therefor having a slot for receiving said projection, said slot having an offset for engaging the projection and holding the catch member elevated, and means carried by the catch member beyond 50 said offset for receiving said projection when the catch member is raised above said elevated position and preventing the projection entering the offset when the catch member is quickly lowered. 55

In testimony whereof I have hereunto set my hand, in the presence of two subscribing witnesses.

FRANCIS C. SOCIN.
